UNITED STATES PATENT OFFICE.

WILLIAM CROOKS, OF PHILADELPHIA, PENNSYLVANIA, ASSIGNOR TO BELMONT PACKING & RUBBER COMPANY, OF PHILADELPHIA, PENNSYLVANIA, A CORPORATION OF PENNSYLVANIA.

MACHINE FOR FOLDING PACKING AND THE LIKE.

Application filed February 5, 1923. Serial No. 617,192.

Packing may consist of a comparatively long and narrow duck and rubber or like sheet folded back and forth on itself with the folds suitably united or cemented and 5 pressed into square or rectangular form in cross-section thus providing strips of what is known as square duck and rubber packing. In the manufacture of such packing the custom has been to fold the sheet by hand, 10 which of course is expensive and slow.

The principal object of the present invention is to fold the strips and, if desired, consolidate the folded strips into square or rectangular form in cross-section.

15 To fold a strip of the character referred to upon itself by machinery presents difficulties among which reference may be made to the length of the strip which necessitates a continuous operation and to the 20 tendency of rolling machinery to cut or tear the strip. My invention comprises machinery which obviates these difficulties and which will be first described and finally 25 claimed at the end hereof.

30 In the description reference will be made to the accompanying drawings illustrating one form of embodiment of the invention but not the only form of embodiment of the invention and in which

35 Figure 1 is a top or plan view with a hand wheel removed.

Fig. 2 is a side view.

Fig. 3 is an end view, partly in section.

40 Figs. 4 and 5 are fragmentary diagrammatic sectional views illustrating the mode of operation.

Fig. 6 is a view of like character illustrating the folded fabric.

45 Fig. 7 is a top or plan view of a feed funnel.

Fig. 8 is a sectional view diagrammatically illustrating a guide.

Fig. 9 is a like view illustrating a modification.

45 Fig. 10 is a top or plan view of a guide, and

Fig. 11 is a sectional view taken on the line 11-11 of Figure 1.

50 There are a series of circumferentially ribbed and grooved rolls in pairs, generally indicated at 1 and 2, between which the strip *a* of appropriate fabric is fed and by which it is progressively folded first at the center (see 1, Fig. 1 and Fig. 4) and then at the

edges (see 2, Fig. 1 and Fig. 5). The ribs 55 of one roll of each pair are disposed in the grooves of the other roll of the pair with space (occupied by a portion of the fabric in Figs. 4 and 5) between the flaring walls with which the ribs and grooves are provided. The number of ribs and grooves increases from the center or center line of the series of pairs of rolls toward the ends of the rolls of the succeeding pairs from the inlet (right in Fig. 1) to the outlet end (left 60 in Fig. 1) of the series. The ribs and grooves of the rolls of one pair are aligned with the ribs and grooves of the rolls of all the other pairs and having reference to the line *a*-*a*, 65 Figs. 4 and 5, of the rolls of the series, the 70 ribs and grooves increase in number toward the ends of the rolls progressively from pair to pair. For example in Fig. 4 there are three ribs and grooves of which one is at the center line and the other two are at the 75 sides of the first. In Fig. 5 the arrangement is the same except that two ribs and grooves are at the sides or ends of the rolls. It may be remarked that the precise number of 80 grooves and ribs is not in all cases essential but the progressive arrangement by which their number is increased from one pair of rolls to the next is important. The bottoms of the grooves are flat and the side walls are flaring. The side walls of the ribs are also 85 flaring but their rims are comparatively sharp. The wheels 22 and 3 and the guided endless bands or straps 4 and 5 are a means for consolidating the folds of the fabric and for imparting to the folded fabric a square 90 or rectangular form in cross-section. The shafts 6 which carry the rolls are mounted in spring pressed bearings 7 carried by a frame or table 8, and they are geared together through idlers 9 and to a power shaft 10. 95 The wheels 22 and 3 are driven one by the shaft 10 and the other by a shaft 11, and these shafts are geared together, and the shaft 11 and the gear on it are the means for connecting the gearing of the rolls with the power shaft 10. Bevel gearing 12 drives the belts 4 and 5 from the shaft 10, and the belts are trained around the driven pulleys 13, the idler pulleys 14, and the adjustable belt tighteners 15, and between the fixed 100 parallel guides 16. The adjustment of the spring pressed bearing 17 of the wheels 22 and 3 can be effected by means of the hand 105

wheel 18 at the front bearing which is connected by sprocket wheels and a chain 19 with the bearing at the back of the machine. 20 are adjustable side guides for directing 5 the strip of fabric to the rolls, and 21 is a spring pressed roller for holding the strip down onto the table. 29 is a funnel guide for feeding the strip to the pair 1 of rolls. 23 is an adjustable guide for directing the 10 strip folded by the pair 1 of rolls to the pair 2 of rolls. 24 is a guide for directing the folded strip to the positively driven endless bands which, in connection with the guide 16, and the wheels 22 and 3, square it or 15 bring it to rectangular form in cross-section. The guide 24 may assume either of two forms. In the case of an even number of 20 folds it may assume the fixed rectangular form shown in Fig. 8, and in the case of an uneven number of folds it may assume the 25 form diagrammatically indicated in Fig. 9 at 24^a in which the side wall 25 is movable and may be spring pressed.

In use a strip is fed between the side 25 guides 20 and under the roller 21 through the funnel 29 to the pair of rolls 1. These fold the center part of the strip, as shown in Fig. 4, and this can be successfully done because the edges of the strip are not confined 30 and can be drawn toward each other, in fact are somewhat drawn toward each other by the funnel 29 to provide the slack or fullness necessary for the folding. The guide 23 prevents the partially folded strip from unfolding and delivers it to the pair 2 of rolls which by folding the side portions of the strip complete the folding operation, and the side portions are free to move toward each 35 other to provide the necessary slack or fullness. The guide 24 (or in the case of the modification) 24^a delivers the folded strip to the endless belts which carrying it through the fixed guides 16 and between the wheels 22 and 3, gives the strip the required consolidation and rectangular form. The deflector 26 may be provided for delivering the 40 finished strip.

It will be obvious to those skilled in the

art to which the invention relates that modifications may be made in details of construction and arrangement without departing 50 from the spirit of the invention which is not limited as to those matters or otherwise than as the prior art and the appended claims 55 may require.

I claim:

1. In a machine for folding packing the combination of a series of pairs of rollers of which the rollers in succeeding pairs are increasingly and cumulatively provided with 60 circumferential grooves and ribs, a pair of pressure wheels at the exit of the pairs of rollers, and endless belts and their fixed guides for delivery from the rollers to the wheels. 65

2. In a machine for folding packing the combination of a series of pairs of rollers of which the rollers in succeeding pairs are increasingly and cumulatively provided with circumferential grooves and ribs, a pair of 70 pressure wheels at the exit of the pairs of rollers, endless belts and their fixed guides for delivery from the rollers to the wheels, and side guides and a roll and a funnel guide at the entrance of the series of rollers. 75

3. In a machine for folding packing the combination of a series of pairs of rollers of which the rollers in succeeding pairs are increasingly and cumulatively provided with circumferential grooves and ribs, a pair of 80 pressure wheels at the exit of the pairs of rollers, endless belts and their fixed guides for delivery from the rollers to the wheels, side guides and a roll and a funnel guide at the entrance of the series of rollers, and 85 guides at the entrance and exit of the last pair of rollers in the series.

4. A machine for folding packing and the like provided with ribbed and grooved rollers in pairs, the ribs and grooves on the second pair of rollers corresponding in alignment with the ribs and grooves on the first pair of rollers plus additional ribs and 90 grooves.

WILLIAM CROOKS.
